AUTOMATIC BAGGER AND LOADER

Walter L. O'Brien, Oak Park, Ill.

Application February 18, 1937, Serial No. 126,495

10 Claims. (Cl. 198—53)

This invention relates to apparatus for loading or dispensing coal or the like.

The retail coal tonnage in the thickly populated residential sections of cities is, to a large extent, delivered in bags containing approximately 100 pounds of coal each. This mode of delivery has been brought about by economic and other conditions such as inaccessible bins excluding the employment of chute or wheel-barrow delivery.

Usually when bags are used today, they are first filled by hand labor in the retailers' coal yards, after which additional labor is required to load the bags onto the usual delivery trucks.

Therefore, an object of my invention is a great saving of time and labor because, in the operation of my apparatus, the trucks are idle for only a few minutes, while in the old method, the trucks would remain idle for a much greater period of time.

The ordinary coal conveyor is well known as consisting of side spaced parallel chains carrying upstanding cross plates which drag the coal from its bottom to the top of its inclined surface, setting up a frictional drag which requires considerable power to operate.

For the purpose of this description, I may, at times, use dimensions to better set out the construction but, of course, no limitations are intended, as other dimensions may be employed for various conditions of practice.

Features of the invention may comprise parallel spaced chains movable on suitable opposite ledges or tracks formed with the side walls of a conveyor structure, and are preferably driven at about 180 feet per minute in a five ton loader when in operation.

The endless chains above described are about 27 feet in length and are provided at intervals of 6 feet with cross connected aprons 3 feet in length and 16 inches wide, and attached to bars connecting the opposite chains, as hereinafter described.

The aprons serve to receive and carry a charge or mass of coal discharged through an opening in the bottom of a hopper, means being provided for adjusting a plate member in said opening and for locking the same for an appropriate area for permitting approximately 100 pounds of coal of the size in the hopper to drop to the conveyor during the interim between the arrival and departure of respective aprons traveling under the hopper and about 6 feet apart.

The hopper and its associated parts comprising the apparatus is preferably portable, having

suitable wheels and a tongue at its front end, where man or horse power may be applied to change the location of the apparatus at will.

Other features of the invention consist in providing scrapers attached to the chains at the rear ends of the coal transferring aprons and a fixed drop-gate for controlling the coal during the run of the chains between the aprons.

Another object of the invention is to provide at the top of the conveyor a bag supporting element, through which the coal is discharged into successive bags placed on suitable supports and removed therefrom by a single operator and at a general speed of 3 seconds per bag, which makes for a maximum saving of time and expense for loading coal in bag lots into trucks for house to house delivery.

Many other features are present which will appear in the following detail description of the elements of the apparatus and in which the expressions and terms employed are of description only and not of limitation.

In the drawings illustrating a preferred form of my invention,—

Figure 1 is a side elevation of the loading and dispensing apparatus, parts being omitted and parts being in section and showing a 100 pound bag suspended from the outlet of a rounded chute on quick acting hooks;

Figure 2 is a fragmentary sectional elevation of the apparatus disclosing some of the important features of construction;

Figure 3 is a fragmentary perspective of a portion of the conveyor frame, showing best the means for adjusting the size of the hopper outlet opening and the means employed for locking the adjusted plate or member;

Figure 4 is a reduced more or less diagrammatic plan view of the chain;

Figure 5 is a longitudinal view of one of the aprons showing the means for attaching it to the chain, and a drag and also shows at its front end a sheet iron scraper for gathering scattered coal, the section being taken on the broken line 5—5 of Fig. 6;

Figure 6 is a fragmentary plan view of the apron showing best the cam-bars of the drag which lift the drop gate just prior to collecting a 100 pound charge of coal on the apron;

Figure 7 is a transverse partial sectional elevation of the conveyor with a drop-gate and its vertical guides;

Figure 8 is a side view of the construction shown in Fig. 7 but showing the action of cam-bars on the drags, raising the gate in its guides

as the drag passes under and through the gate frame or brace;

Figure 9 is a top plan view showing the gate and its guides, with the supporting frame or brace omitted;

Figure 10 is a detail side elevation of one of the hooks for supporting the bags while filling, indicating the releasing swing of a part by dotted lines; and

10 Figure 11 is a perspective detail of a brace.

Referring now to the drawings in detail and more particularly, for the present, to Figs. 1 and 2, 11 designates the improved loader in general, and 12 is a hopper for containing five tons of coal, 15 more or less, provided with a bottom discharge opening 13, its width coinciding with the space between the side walls 14 of a conveyor, generally indicated at 15. The size of the discharge opening may be altered at will for various sizes in 20 coal by an adjustable plate 16 resting on the upper edges of the sides 14 of the conveyor and formed with downturned flanges or side edges 17 for snugly embracing the sides to prevent transverse movements.

25 Pinned, or otherwise secured, as at 18, to the rear portion of the plate 16 is a bar or tongue 19 having a line of holes or perforations 20 of about one inch diameter, and either hole or perforation 20, when the plate is to be adjusted, may register 30 with a central perforation 21 in a cross brace or plate 22, for the passage of a locking bolt 23 which will hold the plate 16 at the desired position for forming the appropriate size of outlet opening for the hopper.

35 Hinged, as at 24, to the under face of the plate 16 near the rear, I provide a plate 26 permitted to swing upwardly only by reason of a stop lug 27. This plate may be weighted as at 28 and its function is to shove back or down all scattered 40 coal lying on the forward part of an oncoming apron to about one third of its length so that the entire load will be dumped quickly, resulting in a faster dumping operation into the bag and giving the operator more time to change bags on the 45 hooks which at most should not be more than three seconds to keep time with the chain or conveyor service.

It should be understood that this is a one man loader for the sake of economy; he stands in his 50 truck with an empty bag on his trip hooks and when a 100 pound charge of coal comes over the top and down through the chute into the bag, he quickly trips his hooks to release the full bag which he guides in its fall into the truck and then 55 immediately grasps an empty bag and places the bag handles or loops over the hooks to receive the next charge following down the chute from the conveyor.

Again referring to Fig. 1, the hopper may be 60 braced on front and rear pairs of wheels 29 and 30 in any manner such as vertical braces 31, 32 and 33 and many more angular braces of various shapes and material as these elements of the apparatus form no part of the invention.

65 The front axle 34 may have a pole 35 of any design and the front wheel hubs may have a swivel connection with their axle (not shown) so that this simple chassis may turn around within reasonable limits. At the top of the conveyor is 70 fixed a dumping chute 36 open at one side and of proper dimensions to permit the outstanding drags to pass around the drive shaft 37 which carries a pair of sprocket wheels, indicated at 38 over which the chains 39 travel and other sprocket 75 wheels 40 on a cross shaft 41 carry the lower part

of the chain 39. The shafts 37 and 41 are mounted in suitable bearings in the conveyor or conveyor frame 15 in the usual manner. Outside of the conveyor frame the power shaft 37 has fixed to rotate therewith a power sprocket 42 connected to a motor sprocket 43 through a chain 44. In the size of the apparatus above described, a 5 horse power motor has been found adequate for the power desired.

Secured to the lower part of the discharge chute 10 36 and at opposite sides thereof is a pair of two-part bag hooks 45 of simple yet effective design, and each comprises an L-shaped inner part 46, the vertical leg of which is welded or otherwise secured to the chute wall, while the horizontal 15 load supporting leg 47 terminates in a rolled eye or bearing 48 for receiving a hinge pin 49 on which the outer swingable part 50 of the bag hook is carried.

When the hook (see Fig. 10) is supporting a 20 coal bag 51, the loops or handles 52 at either side thereof are placed over the arm or wing 53 of the said swingable member and allowed to rest on another arm 54 of the outer member, and this arm rests on the horizontal arm 47 of the inner 25 fixed part and when the operator wants to release a full bag from the hooks quickly, the thumbs of the operator should be used to force the top of the outer hook part outwardly on its pivot 49 when the loops will be carried outwardly and 30 over the end of the part 47 of the hook.

The delivery chute 36 may also carry at its bottom a wide horizontal ring 55 to assist the operator in spreading the bags just prior to their delivery to the hooks and for maintaining the 35 tops of the bags open while the coal is passing, for avoiding collapse and the spilling of coal over the tops of the bags.

Fixed to the conveyor frame 15 at a determined 40 distance below the hopper opening 13, I provide a drop-gate 56, best shown in Figs. 2, 7-9, its purpose being to stop all coal falling from the hopper opening from running downward of the conveyor at the time 100 pounds of coal is collecting in front of the gate on a stationary floor 57 extending 45 across the conveyor on a level with the chain tracks or supports 58. The extension of this floor should be about as shown in Fig. 2.

Anchored by appropriate means in the conveyor framework 15 are opposite guide posts 59 having 50 continuous guide channels 60 for receiving short rollers 61 mounted on a cross bar or shaft 62 and mounted in loop supports 63 riveted or otherwise fixed to a drop door 64, as at 65.

Extending into the channels 60 and normally 55 near the lower ends of the guide posts 59 are opposite elongated rollers 65' extending inwardly from the guide posts to provide inner portions 66 for engagement by cam-bars 67 for raising the gate, as and for the purpose later described. The 60 elongated rollers 65' are carried on a cross bar 68 (Figs. 7 and 8) mounted in looped straps 69, riveted to the drop door 64, as at 70.

The frame structure of the conveyor at the 65 location of the drop gate 56 is set out at the lower sides as at 71, to receive the chains 39 so that no coal contacts them and this set out of the frame is continued throughout the length of the chain tracks or supports 58.

The conveyor chain and its three spaced coal carrying aprons will now be described. The chain as above set out is employed for the greater part of its length for traction only, but where the aprons are attached it performs the two- 75

fold purpose of traction and carrier of coal units of approximately 100 pounds on each apron. The aprons, indicated generally at 72, are preferably three in number, 3 feet long and are separated along the chains length by 6 foot spaces 13. The aprons 72 are similar and are supported by a series of cross bars 73' preferably having rounded lower faces 74 and flat top faces 75 to which the apron proper 76 constructed of a suitable tough composition material may be secured by rivets 77, or other fastenings. The rear end of the apron is shown as riveted or otherwise fastened to a cross bar 78, cross connecting the side walls 79 of an upstanding drag 80 having a plane rear wall 81, and at the sides of the drag, at the top, are secured downwardly and forwardly inclined cam-bars 67 for raising the drop-gate 64 at intervals. The drag and cam-bars are shown as connected by braces 82 and the front ends of the cam-bars simply rest on one of the cross bars 73' as shown in Figs. 5 and 6. The leading edge of the apron 72 carries a metal scraper 83 comprising a flat portion 84 and a portion 85 projecting down at about 30° to within a short distance of the floor 57 from which the coal is collected onto the apron. The body portion 84 of the scraper 83 rests on two cross bars 86 to which it is riveted as at 87.

In Figs. 5 and 6 is shown the sides 79 of the drag as provided with thin link extensions 88 which fit over the chain pins 89 which may be made longer and riveted to said thin link for securing the drag to the chain, or other means may be employed for this purpose.

To properly maintain the guide posts 59 in a vertical position (Figs. 7 and 8), I employ a brace 90 entirely embracing the conveyor structure where the drop-gate 64 operates. The gate is normally held a short distance from the floor by any suitable means to permit the inclined scrapers leading the aprons to enter under the gates and under the collected coal just ahead.

I claim:

1. A coal loader comprising in combination with a hopper having a supporting gear, an inclined conveyor frame disposed under a discharge opening of the hopper, sprockets in pairs mounted at each end of the frame, chains on said sprockets, a floor under said chains, a normally closed drop gate fixed over the lower end portion of the floor, for collecting at intervals charges of determined bulk from said hopper, flexible aprons connected across to the chains, scrapers and drags secured to the respective front and rear ends of said aprons for moving coal collected at intervals back of said gate, and inclined bars on said drags for lifting the drop gates as the chains draw the aprons thereunder for delivering coal upwardly.
2. A coal loader comprising with a supply hopper having a supporting running gear, an inclined conveyor frame disposed under a hopper opening, sprockets in pairs mounted at each end of said frame, chains on said sprockets, flexible aprons on said chains, scrapers fast to the leading edges thereof for collecting determined charges of coal, drags having upstanding rear and side walls secured on the rear ends of said aprons for assisting the aprons in the collecting of coal deposits at intervals when the chains are operating, a normally closed drop gate, rollers projecting from the sides of the gate, fixed vertical guides for receiving said rollers, said drags also being provided with inclined bars for contacting the gate rollers for raising the gate when the

chains are operating in drawing the aprons and drags upwardly towards the hopper outlet at intervals.

3. A coal loader comprising with a supply hopper having a supporting running gear, an inclined conveyor frame disposed under a hopper opening, sprockets in pairs mounted at each end of said frame, chains on said sprockets, flexible aprons on said chains, scrapers fast to the leading edges thereof for collecting determined charges of coal, drags having upstanding rear and side walls secured on the rear ends of said aprons for assisting the aprons in the collecting of coal deposits at intervals when the chains are operating, a normally closed drop gate, rollers projecting from the sides of the gate, fixed vertical guides for receiving said rollers, said drags also being provided with inclined bars for contacting the gate rollers for raising the gate when the chains are operative in drawing the aprons and drags upwardly towards the hopper outlet at intervals, said flexible aprons being fixed to and spanning the innermost edges of the chains eliminating injurious contact of coal over the chains, said chains being connected by cross bars under the aprons and centrally secured thereto by rivets, said bars having reduced ends for forming trunnions extending through alternate links of the chains, and means at the rear end of the aprons for bracing said aprons between the side drag walls.

4. A coal loader comprising a hopper provided with a discharge opening, a conveyor having traveling chains underlying the hopper opening, means resting and movable on the sides of said conveyor for locking adjustment for the size of said opening, a floor extending across the conveyor below said opening, a gate at the lower part of the floor and below the opening for collecting coal dropping on said floor, aprons on said chains for entering under said gate and under the said coal, and a drag connected to each of said aprons for raising said gate and for carrying the coal thus collected to the delivery end of the conveyor.

5. A coal loader comprising a hopper having a discharge opening, a conveyor arranged under said opening, means for locking adjustment of its size, chains running at the sides of the conveyor, flexible aprons spaced longitudinally on said chains, a metal scraper attached to the leading end of each apron and an upstanding drag attached to the rear end of each apron, a drop-gate for collecting coal dropping from the hopper, cam-bars on said drags for successively raising said drop-gate for removing said collected coal, and means for driving said chains.

6. A coal loader comprising a hopper having a discharge opening, in combination with an inclined conveyor arranged under said opening, a plate projecting into said opening and means for locking the plate in desired adjusted positions for changing the size of said opening, chains extending through the conveyor, a floor arranged under said opening in the hopper, a drop-gate arranged across the conveyor, spaced coal carriers on the chains, drags on said carriers for raising the gate and collecting coal, and means for driving the chains.

7. The combination with a supply hopper having a discharge coal opening, of an inclined conveyor disposed beneath said opening, slidible means on the conveyor for adjusting the size of said opening; a conveying device operating in said conveyor, a liftable gate for collecting coal

falling from the hopper opening, a series of coal supporting aprons spaced from each other on the conveying device a distance greater than their respective lengths, a scraper on the forward end 5 of each apron, a drag on the rear thereof, means on said drag for raising said gate, said scraper, apron and drag cooperating for scooping up a charge of coal resting back of said gate and conveying the same over the top of the conveyor, and 10 means driving the conveying device.

8. The combination with a supply hopper having a coal discharge opening, of an inclined conveyor, chains running therein, aprons on said chains, a swing gate for brushing back scattered 15 coal near the forward end of said aprons when passing, a drop-gate located to gather coal falling from the hopper, means at the rear of each apron for raising the drop-gate and gathering the coal back of said gate, and means for operating the chains for conveying the coal thus gathered over the top of the conveyor.

9. A coal loader comprising an inclined conveyor having upstanding parallel sides; spaced conveying devices running therebetween, a floor 20

between said devices and extended under the same, a drop gate near the forward end of the floor, a backwardly swingable stop plate near the rear end of said floor, flexible aprons fast on said devices, means for feeding coal onto said floor back of said drop gate, means at the rear of each apron for raising the drop gate and said stop plate as the successive aprons pass with charges of coal thereon.

10. Means for distributing coal into bags of like 10 capacity from a common supply, comprising a conveyor, a floor for receiving a continuous downward flow of coal from said supply, a drop gate for collecting said coal on said floor, flexible aprons constituting a part of said conveyor, 15 scrapers and drags constituting cooperative parts of said aprons, a swingable weighted stop plate for preventing the spread of coal on said aprons, and means on said drags for raising the drop gate and stop plate in the passage of successive 20 charges of coal on the aprons, and means for guiding the charges into successively provided bags.

WALTER L. O'BRIEN.
